THREAD FEED ARRESTING DEVICE

John T. Gordon and Raymond E. Solliday, Akron,
Ohio, assignors to Wingfoot Corporation,
Akron, Ohio, a corporation of Delaware

Application October 10, 1946, Serial No. 702,526

2 Claims. (Cl. 57—86)

1

The present invention relates to an improved form of thread feed arresting device for use in conventional thread manipulating apparatus. More particularly, the invention pertains to an automatically operable device which acts whenever one of several moving threads, yarns, or the like or the composite thread bundle formed therefrom is broken or otherwise interrupted to cut simultaneously all of the individual threads being fed through the device.

The thread feed arresting device of the invention is particularly advantageously adapted to be employed in the conventional doubler-twister machines which serve to ply together a plurality of individual threads to form a composite thread bundle. In such operations it is essential to stop the thread plying operation in the event that one or more of the individual threads being plied up becomes broken or the supply thereof is otherwise interrupted so as to prevent the running of less than the desired number of threads. It is also desirable to stop the operation of such apparatus if the composite thread bundle being formed should become broken.

Certain types of thread feed arresting devices are already available in the industry for accomplishing one or the other of the above-mentioned operations. None of the conventional devices, however, is known to have effectively combined both operations to insure the successful operation of the thread manipulating apparatus with which it is associated.

It is, therefore, an object of the present invention to provide a thread feed arresting device for simultaneously cutting the several individual threads as they pass through the manipulating apparatus in the event that the supply of one or more of said threads is inadvertently interrupted or the composite thread bundle formed by plying together the several threads becomes broken.

It is a further object of the present invention to provide a highly efficient and economically manufacturable device for arresting thread feeding operations which will have universal application in any of several conventional forms of thread manipulating equipment.

Other objects and advantages of the invention will become apparent as the description of one form of device embodying the principles of the present invention proceeds.

In the drawings, Fig. 1 shows a conventional type of thread manipulating apparatus employing one form of thread feed arresting device embodying the teachings of the present invention. Fig. 2 is a side elevation of the thread feed ar-

2

resting device of the invention at a somewhat larger scale. Figs. 3 and 4 correspond generally to Fig. 2, but illustrate the disposition of the several operating elements of the device in their respective operating positions. Fig. 5 is a plan view of the device of Fig. 2 as seen from the line 5—5.

In Fig. 1 of the drawings, the reference numeral 1 identifies a conventional form of doubler-twister apparatus employed in the manufacture of thread, cord, and the like from a plurality of individual threads or strands. The doubler-twister apparatus 1 embodies, among other things, a frame 2 which carries a spindle support 3 thereon. The spindle support 3 is provided with a plurality of spindles 4 and guide bars 5 which are arranged in substantially vertical rows and disposed in spaced, mutually parallel relation to each other so as to extend in a substantially horizontal position from the spindle support 3.

Each of the spindles 4 carries a supply spool 6, 7, 8, each of which provides an individual strand or thread end 9, 10, 11 for incorporation into a finished doubled and twisted thread bundle or cord. The threads 9, 10, 11 from each of the several spools 6, 7, 8, respectively, are directed through a guide 12, one of which is provided for each series of supply spools and mounted upon the longitudinally extending base portion of the spindle support 3 on the frame 2 of the machine. The several threads 9, 10, and 11 are drawn together in mutually parallel relation by the guide 12 in which form they are thereafter subjected to any one of several different processing treatments and finally twisted into a finished composite thread bundle or cord.

In accordance with conventional procedure in the manufacture of a composite thread bundle or cord, the bundle is passed over a freely rotatably mounted roller 13 which is supported by a longitudinally extending shaft 14 in such a way as to enable it to dip into a tank 15 of suitable processing liquor. It will be readily understood that the processing liquor employed in the tank 15 may take the form of certain adhesive materials or lubricating liquids which facilitate the twisting together of the individual threads 9, 10, and 11 into a finished composite thread bundle and insure that the projecting fibers in the individual threads will be held in place in the bundle.

In the illustrated form of doubler-twister apparatus 1 shown in Fig. 1, the individual threads 9, 10, and 11, after being subjected to processing treatment on the roller 13, pass through the thread feed arresting device 16, under the driven

rolls 17 and 18, over the weighted roller 19, and through the pigtail guide 20 to a collecting means 21 with the aid of which the composite thread bundle is collected in the form of a precision-wound package upon a spool 22. The collecting means indicated generally by the reference character 21 embodies a rotatably mounted pulley 23 on which the spool 22 is mounted for rotation. The pulley 23 is supported by a stationary rail member 24 and driven by a belt 25. The composite thread bundle is built up in the form of a precision-wound package by means of a ring twister mechanism embodying a ring 26 mounted upon a ring rail 27 which is reciprocated in a direction axially of the spool 22. The ring 26 carries a traveler 28 through which the composite thread bundle is directed to the spool 22 in the laying up of the thread package 29.

The thread feed arresting device 16 of the present invention has a frame member which is provided with a mounting flange 31 facilitating its disposition in the doubler-twister apparatus 1 in proper operating relation with respect to the driven feed rolls 17 and 18. A series of guide eyes 32, 33, and 34 are formed on weighted lever arms 35, 36, and 37, respectively, for the reception of the individual threads 9, 10, and 11 from the supply spools 6, 7, and 8. The several threads 9, 10, and 11, after passing through the guide eyes 32, 33, and 34, are drawn together in the form of a composite thread bundle 38 by the guide 39 through which they next pass. From the guide 39, the composite thread bundle 38 next passes under the roller guide means or abutment 40 which is freely rotatably mounted upon the headed pin 41 secured to the frame member 30 of the thread feed arresting device 16.

The composite thread bundle 38, after passing under the abutment 40, is carried upwardly in contact with the driven feed roll 17 (see Fig. 2), around the weighted roller 19, and thereafter in contact with the driven feed roll 18 from which it is directed over the grooved roller guide 42 to the pigtail guide 20 and the collecting means 21 of the doubler-twister apparatus 1. The grooved roller guide 42 is freely rotatably supported by a swingably mounted arm 43 arranged to pivot about a pivot pin 44 secured to the frame member 30 of the thread feed arresting device 16. The arm 43, as will be seen from Fig. 4, is normally biased toward the uppermost position of its pivotal movement about the pivot pin 44 by means of the tension spring 45, one end of which is affixed to the arm 43 adjacent its pivoted mounting, while the other end is secured to the frame member 30. The running composite thread bundle 38, when it is passed over the grooved roller guide 42, tends to bias the arm 43 into its lowermost position as illustrated in Fig. 2 of the drawings against the action of the spring 45.

A slide bar or rod 46 is mounted on the face of the frame member 30 of the thread feed arresting device 16 so as to be slidable in a horizontal position in the mounting means 47 and 48. The rod 46 is normally urged toward the right as seen in Figs. 2 and 3 of the drawings by means of a compression spring 49 disposed between the face of the mounting means 47 and the collar 50 secured to the rod 46. The rod 46 is provided with a squared end portion 51 which registers with a notched portion 52 of an insert 53 provided at the pivotally mounted end portion of the arm 43 when the composite thread bundle 38 is running over the grooved roller guide 42, and the several individual threads 9, 10, and 11 are 70

properly passing through the doubler-twister apparatus to the collecting device 21.

On the right hand end of the rod 46 and adjacent the mounting means 48 is mounted a trip means or sleeve 54 which is provided with limited movement in a direction axially of the rod 46 by means of the slotted hole 55 with which the pin 56 inserted in the rod 46 registers. The sleeve 54 is so disposed with respect to the weighted lever arms 35, 36, and 37 that the projecting portions 57 thereon will contact the sleeve and cause it to move axially of the rod 46 when one or more of said lever arms swing downwardly about their pivotal mounting upon the frame member 15 30 of the thread feed arresting device 16.

A suitable severing means or knife 58 is secured to a counterweight member 59 which is rotatably mounted about a pivot pin 60 secured to the frame member 30 in such a way as to enable the knife to contact the abutment 40 when the counterweight is in the lowermost position of its arcuate path about the pivot pin 60. In the normal operation of the doubler-twister apparatus 1, the knife 58 is held out of contact 20 with the abutment 40 as by means of a holding means or pawl 61 which engages a notch 62 in the counterweight 59. The pawl 61 is pivotally mounted about a post 63 secured to the frame member 30 and has a small weight 64 secured thereto for insuring the engagement of said pawl with the notch 62 in the counterweight 59 when the device is being threaded up.

The threading up of the thread feed arresting device 16 is facilitated by the provision of a locking means 65 which takes the form of a lever arm mounted for pivotal movement about a pivot pin 66 secured to the frame member 30 of the device. A pin 67 in the counterweight 59 extends outwardly at right angles to the face of the frame member 30 for contact with the free end portion of the locking means 65. The movement of the locking means 65 is restricted by the limit pins 68 secured to the face of the frame member 30 above and below the locking means and a hole 45 69 drilled in the locking means is adapted to register with the conically shaped pin 70 to enable the locking means to be held against the lowermost limited pin 68 during the threading up operations against the action of the tension spring 50 71.

It will be readily understood that the conventional double-twister apparatus comprises a series of individual operating stations arranged axially along the machine in spaced, generally parallel relation. Each of these stations comprises a plurality of supply spools 6, 7, and 8, the dip roll 13, thread feed arresting device 16, weighted roll 19, and thread collecting device 21, while the driven feed rolls 17 and 18 extend longitudinally of the apparatus and serve to draw the individual threads 9, 10, and 11 from their respective supply spools 6, 7, and 8, to form the same into the composite thread bundle 38 for collection in the form of a precision-wound thread package 29 60 on the collecting device 21.

As will be noted from Figs. 2 and 5, the ends of the individual threads 9, 10, and 11 are threaded through the eyes 32, 33, and 34, respectively, on the weighted lever arms 35, 36, and 37. In the threading up operation, the locking means 65 is disposed in contact with the lowermost limit pin 68 by registration of the hole 69 with the pin 70, thereby temporarily holding the counterweight 59 in the uppermost position of its arc with respect to its pivot pin 60 by reason of the contact 70 75

of the free end of the locking means with the pin 67 therein. Thus, the several threads are enabled to be passed through the guide 39, under the abutment 40, under the feed roll 17, over the weighted roll 18, and finally under the feed roll 18.

The composite bundle 38 formed of the individual threads 9, 10, and 11, after passing under the feed roll 18, is then directed over the grooved roller 42, causing the same to swing downwardly against the action of the spring 45 and permitting the squared end portion 51 of the rod 46 to register with the notch 52 in the insert 53. After the end of the composite thread bundle 38 has been fastened to the collecting spool 22 of the collecting means 21, the locking means 65 may be released from its engagement with the pin 10, thereafter bringing all of the operating elements of the thread feed arresting device 16 into the relationship illustrated in Fig. 2 of the drawings.

As will be seen from Fig. 2, the individual threads 9, 10, and 11 now support the weighted lever arms 35, 36, and 37 against the weights thereon while the composite thread bundle 38 passing over the grooved roller guide 42 holds the swingably mounted arm 43 in its lowermost position about the pivot pin 44. In the event that there should be any interruption in the supply of any one of the individual threads 9, 10, or 11, the weighted lever arm associated with that individual thread will be depressed by the action of the weight. Such an instance is illustrated in Fig. 3 in which the supply of the individual thread 10 is supposedly broken, thereby permitting the lever arm 36 to drop downwardly, causing the projecting portion 51 thereon to contact the end of the sleeve 54 adjacent thereto.

The action of the contact of the projecting portion 51 of the arm 36 with the sleeve 54 causes the latter to move in a direction axially of the rod 46 or toward the left as illustrated in Fig. 3 until the pin 56 registers with the right hand extremity of the slotted hole 55. This movement of the sleeve 54 brings the left hand extremity thereof into contact with the pawl 61 causing it to become disengaged from the notch 62 in the counterweight 59, thereby permitting the knife 58 to swing about its mounting on the pivot pin 60 and causing it to contact the abutment 40 abruptly cutting the remaining individual threads 9 and 11.

It will be seen that the above-described operation of the thread feed arresting device 16 thus prevents "singling" or the running of fewer than the required number of component threads in the fabrication of a composite thread bundle. The severed end of the composite thread bundle 38 will run through the apparatus to the collecting spool 22 and, thereafter, that particular station on the double-twister apparatus 1 will cease to operate until the cause of the interruption in the supply of the individual thread 10 has been corrected and the machine again threaded up in the manner previously described.

The thread feed arresting device 16 of the present invention, in addition to preventing the singling operation, operates upon the breaking of the composite thread bundle 38 to cut simultaneously all of the individual threads 9, 10, and 11 passing therethrough, thus preventing any possibility of the free end of the composite bundle becoming entangled with adjacent positions or stations on the double-twister apparatus. It will be understood that if the broken end of the thread bundle 38 were to continue to feed through the apparatus after the bundle ceases to be collected upon the collecting spool 22, the collecting pack-

ages 29 at adjacent stations on the machine could become fouled by the freely running end of the bundle. Fig. 4 of the drawings illustrates in part the operation of the thread feed arresting mechanism 16 of the present invention upon the breaking of the composite thread bundle 38.

As the composite thread bundle 38 is broken, the tension on the grooved roller guide 42 is instantly released, thereby permitting the tension spring 45 to cause the arm 43 to swing upwardly toward the uppermost limit of its movement about the pivot pin 44. This action of the arm 43 causes the squared end portion 51 of the rod 46 to become disengaged from the notch 52 in the insert 53, thereby causing the rod 46 to be urged toward the left, as shown in Fig. 4 of the drawings, compressing spring 49. This axial movement of the rod 46 causes the pin 56 to engage the left hand end of the slotted hole 55 in the sleeve 54, resulting in the contact of that end of the sleeve 54 with the pawl 61. The movement of the pawl 61 causes it to become disengaged from the notch 62 in the counterweight 59, permitting the counterweight to swing downwardly and bringing the knife 58 into contact with the abutment 40 immediately severing all of the individual threads 9, 10, and 11 simultaneously.

The thread feed arresting device 16 of the present invention thus achieves a two-fold purpose, namely the preventing of the running of fewer than the required number of individual threads to be formed into a composite bundle as well as the discontinuance of operation of the feed rolls upon the breaking of the composite thread bundle. It will be readily understood that certain modifications may be made in the structure of the thread feed arresting device without in any way departing from the spirit or scope of the invention.

While in accordance with the patent statutes one best known embodiment of the invention has been illustrated and described in detail, it is to be particularly understood that the invention is not limited thereto or thereby, but that the inventive scope is defined in the appended claims.

We claim:

1. Thread feed arresting mechanism for controlling the travel of thread and the like through apparatus embodying the delivery of individual threads from each of a plurality of supply packages to a collecting means on which said threads are collected in the form of a composite thread bundle, said arresting mechanism comprising an abutment about which the individual threads pass; severing means co-acting with the abutment for simultaneously cutting all of the individual threads; means swingably supporting the severing means; means holding the severing means out of contact with the abutment; trip means for releasing the holding means and causing the severing means to operate; a weighted lever arm supported by each individual thread for actuating the trip means upon the interruption of the supply of said thread; a guide means in contact with which the thread bundle passes; biasing means for retracting the guide means which actuates the trip means when the thread bundle is broken; and disengageable locking means for temporarily retaining the several elements of the mechanism in inoperative relation until the mechanism has been completely threaded up.

2. A thread feed arresting device for controlling the travel of thread in an apparatus embodying the delivery of individual threads from each of a plurality of supply packages to a collecting means

on which said threads are collected in the form of a composite thread bundle, said device comprising a frame; a plurality of individually weighted thread feed guides pivotally mounted on the frame; a delivery guide also pivotally mounted on the frame; an abutment on the frame against which the threads from the individual feed guides pass in their paths of travel to the delivery guide; a counterweighted cutter pivotally mounted on the frame for engagement with the abutment; means temporarily holding the cutter out of engagement with the abutment; trip means slidably mounted on the frame for displacing the holding means to release the cutter, said trip means being actuated by any one of the feed guides and the delivery guide; and disengageable locking means on the frame for engaging the cutter and

preventing the unauthorized release of the cutter as the guides are threaded up.
